(57) **CLAIM**

The ornamental appearance for a portion of a forehead pad assembly, as shown and described.

DESCRIPTION

FIG. 1 is a rear perspective view of a portion of a forehead pad assembly according to our design;

FIG. 2 is a front perspective view thereof;

FIG. 3 is a front view thereof;

FIG. 4 is a rear view thereof;

FIG. 5 is a right side view thereof, with the left side thereof being a mirror image thereof;

FIG. 6 is a top view thereof, with the bottom view being a substantial mirror image thereof; and,

FIG. 7 is a rear perspective view of the portion of the forehead pad assembly in a connected state with a forehead support.

Throughout the various figures of the drawings, certain views may not be provided. The omission of a particular view is intended to convey that the element(s) depicted is/are plain and unornamented in that omitted view, or that the particular ornamental appearance in that view is not claimed.

Where included, broken lines showing environment or structure are for illustrative purposes only and form no part of the claimed design.
